United States Patent Office

Des. 219,787
Patented Jan. 26, 1971

219,787

FURNITURE PANEL OR SIMILAR ARTICLE

Douglas Ian MacFarlane, 20508 Clark St.,
Woodland Hills, Calif. 91364

Filed Aug. 18, 1969, Ser. No. 18,754

Term of patent 14 years

Int. Cl. D6—01

U.S. Cl. D33—1

FIG. 1

FIG. 2

FIG. 3

FIG. 4

FIG. 5

FIG. 1 is a perspective view of a furniture panel or similar article showing my new design;

FIG. 2 is a front elevational view thereof;

FIG. 3 is a rear elevational view thereof;

FIG. 4 is a side elevational view thereof, the opposite side being the same as the side shown; and,

FIG. 5 is a top plan view thereof, the bottom view being the same as the top shown.

I claim:

The ornamental design for a furniture panel or similar article, substantially as shown and described.
